UNITED STATES PATENT OFFICE.

DELBERT B. DREESE, OF LARNED, KANSAS.

DUST CAP FOR TIRE VALVES.

Application filed October 16, 1920. Serial No. 417,382.

To all whom it may concern:

Be it known that I, DELBERT B. DREESE, citizen of the United States, residing at Larned, in the county of Pawnee and State 5 of Kansas, have invented certain new and useful Improvements in Dust Caps for Tire Valves, of which the following is a specification.

This invention relates to an improved 10 dust cap for tire valves and has as one of its principal objects to provide a device of this character which will eliminate the tedious task of threading the cap upon the valve casing so that the cap may be readily applied and removed.

A further object of the invention is to provide a cap employing a securing spring arranged to coact with the valve casing for binding the cap thereon.

20 And the invention has as a still further object to provide a cap wherein the securing spring may be readily fitted in the cap or removed therefrom but wherein said spring will normally be held securely within the 25 cap.

Other and incidental objects will appear hereinafter.

In the drawings:

Figure 1 is a fragmentary sectional view 30 showing my improved cap applied to a tire valve of conventional design, a portion of a wheel being illustrated,

Figure 2 is a transverse sectional view on the line 2—2 of Figure 1, looking in the 35 direction of the arrows,

Figure 3 is a perspective view showing the securing spring for the cap in detail, and

Figure 4 is a transverse section on the 40 line 4—4 of Figure 1, looking in the direction of the arrows.

In carrying the invention into effect, I employ a cylindrical shell 10 preferably constructed of suitable metal and provided 45 throughout the major portion of its length, as particularly shown in Figure 2, with a series of angular faces. The shell is open at its lower end and closed at its upper end and pressed in from the wall of the shell 50 at the upper ends of the angular faces thereof is an annular shoulder or rib 11. Removably fitting in the shell is a securing spring therefor. As shown in detail in Figure 3, said spring comprises a flat spring 55 tongue 12 which throughout the major portion of its length is bowed longitudinally.

The upper end portion of the tongue is straight and integrally formed thereon or otherwise secured to said tongue is a split resilient anchoring ring 13. This ring is 60 positioned within the shell above the shoulder 11 thereof and the normal external diameter of the ring is slightly greater than the internal diameter of the upper end portion of the shell so that said ring will frictionally coact with the shell for securing the spring therein, the curved lower end portion of the tongue bowing inwardly away from the shell. As will be perceived, the curved upper end wall of the shell will 65 coact with the ring 13 for holding the spring against upward movement while the shoulder 11 will coact with the lower edge of the ring for sustaining the spring against downward movement so that possibility of 70 accidental displacement of the spring will be effectually overcome while, at the same time, the spring will also be held against longitudinal shifting within the shell. However, by grasping the free end of the 75 tongue and exerting sufficient pulling force on the ring 13 may be caused to ride over the shoulder 11 so that the spring may be displaced. Consequently, should one spring become broken or its efficiency otherwise impaired, a new spring may be readily substituted therefor. To insert a new spring in the shell, it is simply necessary 80 to push the spring inwardly within the shell until the split ring of said spring is 85 caused to ride over the shoulder of the shell when the ring will then, as previously explained, coact with the shell for holding the spring therein. In this connection, it is to be noted that the straight upper end 90 portion of the tongue is formed to fit, as shown in detail in Figure 4, between a pair of the angular faces of the shell so that as will be seen, the straight upper end portion of the tongue will coact with said 95 faces for holding the split ring 13 against rotative movement within the shell. Consequently, the tongue 12 will be prevented 100 from shifting about the axis of the shell. In the drawing, I have shown my improved cap in connection with the tire 105 valve of a conventional tire. The valve casing is indicated at 14 and as usual, this casing is formed with a pair of oppositely disposed flat faces 15. Closing the casing 110 at its upper end is the usual cap 16. The casing is shown as fitted through a wheel

felly 17 of ordinary construction and threaded upon the casing to seat against the inner face of said felly is the customary nut 18. As will now be seen, the shell may be slidably fitted over the projecting outer end portion of the casing and the tongue 12 brought to bear against one of the flat faces 15 thereof when the tongue will coact with the casing for securely holding the shell thereon. Since the spring is, as previously explained, locked against rotation within the shell, the tongue will coact with the confronting flat face of the casing to, in turn, lock the shell against rotation upon the casing while rotative creeping of the spring will be prevented such as might possibly cause the tongue to ride off of the flat face of the casing. In removing the shell it may, of course, simply be withdrawn from over the casing. I accordingly provide a dust cap of highly effective design and a cap which may, as will now be clear,

be readily employed in connection with substantially any conventional design of tire valve.

Having thus described the invention, what is claimed as new is:

A dust cap for tire valves including a shell having an internal shoulder near its outer end and provided with flat angular faces, and a securing spring for the shell having a split resilient ring expanded within the shell above said shoulder for engaging the inner circumferential wall of the shell and holding the spring within the same, and a tongue extending from said ring and provided with a straight portion at the ring lying between two flat faces of the shell whereby said faces will coact with the edges of the straight portion of the spring to hold the spring against relative rotation within the shell.

In testimony whereof I affix my signature.
DELBERT B. DREESE. [L. s.]
